HUGH FRANKLIN SHEDD, OF MINNEAPOLIS, MINNESOTA

PERPETUAL CALENDAR

Application filed June 17, 1932. Serial No. 617,885.

This invention is directed to an improvement in calendars of the perpetual type, wherein the days of the month or other successive data is arranged on leaves which are 5 successively exposed in accordance with the particular and appropriate data, the invention being more particularly to convenient means for permitting successive exposure of the leaves, with such means arranged to accommodate the bodily movement of all leaves 10 from one position to another as is necessary in the reuse of the data contained on the leaves.

The primary object of the present invention is the provision of a holding clip cooperating with the backing for a swinging and sliding movement, the clip being formed to engage all of the leaves in unexposed position and operable through a swinging movement, together with a particular formation of each 20 leaf to permit a single leaf to drop to exposed position, each reverse swinging movement of the clip freeing the succeeding leaf, the sliding movement of the clip freeing all leaves or permitting the clip to be arranged in a position 25 for the return of all leaves previously exposed to an inoperative position for successive use of the data on said leaves.

The invention is illustrated in the accompanying drawing, wherein:—

Figure 1 is a perspective view of the calendar, the clip being shown in card-holding position.

Figure 2 is a broken perspective view showing the upper portion of the leaves and the clip in cooperation therewith in full lines, the clip being shown in dotted lines in one position to release the outermost card and in another position free of all cards.

Figure 3 is a broken perspective view of the upper portions of several successive leaves showing the relation of the notches therein with which the clip cooperates in freeing successive leaves.

Figure 4 is a broken plan of the calendar showing the mounting and limiting slot for the clip.

Figure 5 is a sectional view showing the mounting of the guides for the cards.

The invention is particularly concerned 50 with the holding clip, but in order to illus-

trate its function and operation it is shown in use in connection with a perpetual calendar of a particular type. It is to be understood, however, that the particular type of perpetual calendar is of no importance in connection with the present invention so long as such calendar includes leaves bearing successive calendar data which is to be moved from an inoperative position to an operative position to expose that data.

For the sake of an understanding of the invention, however, the calendar illustrated will be briefly described as including a backing 1, which is preferably made up of superimposed sheets bound at the edges and between which on one side is arranged a disk 2 bearing the names of the days of the week, with such names capable of selective exposure through an opening 3 in the facing sheet of the backing, a similar disk 4 bearing the names of the months of the year, and with such names selectively exposable through an opening 5 in the facing sheet of the backing, being also provided so that the appropriate day and month may be exposed to view by simple manual manipulation of the respective disks, as is well understood. On the facing sheet of the backing are arranged spaced guide strips 6 on which the calendar leaves to be hereinafter described are mounted. These strips, here shown as narrow strips of sheet metal, have their lower ends underlying the facing sheet of the backing, with the terminal ends passed through openings in such facing sheet and turned down, as at 7, to hold the strips in place. The strips above the turned down ends are extended outwardly from the backing, as at 8, and upwardly parallel to the backing, as at 9, then inwardly toward the backing, as at 10, with their free ends turned up in short sections 11 which rest directly on the facing sheet of the backing.

The guide strips are more or less resilient so that the sections 11 remain in contact with the backing and yet are capable of being manually pressed away from the backing for the insertion or removal of the leaves. As formed, the guide strips present rectangular sections having upper and lower portions at

right angles to the face of the backing with which the respective leaves may cooperate.

10 The leaves, indicated at 12, are provided on their calendar data side with numbers corresponding to the days of the months, and near one edge each leaf is formed with slots 13 to slidably cooperate with the guide strips 6. The leaves when in inoperative position rest against the backing above the guide strips, the slots then cooperating with the in-turned portion 10 of each guide strip. As the leaves are delivered from an inoperative to an operative position, they are moved or permitted to move over the vertical or up-standing portion 9 of the guide strips onto the outstanding portion 8 at the lower ends of the strips from which the leaves depend, with the calendar data, which is concealed in the inoperative position of the leaf, fully exposed to indicate the number of the day, and the week and month shown through the proper operation of the disks 2 and 4, as previously described.

As the calendar is ordinarily supported in vertical position, it is apparent that the foremost leaf, when released from being held in an inoperative position, as will be later described, will gravitate to an operative position. Therefore, in changing the calendar from day to day, it is necessary to only release the outermost leaf of the leaves in inoperative position and permit such outermost leaf to gravitate to an operative or exposed position. When the period for which the data on the leaves expires as, for example, at the end of the month, it is necessary to return all of the exposed leaves from their operative position to an inoperative position to indicate the data of the successive months. Thus, the calendar, to be conveniently effective, must provide means for successively releasing single leaves from the inoperative position for the exposure of their data in the operative position, while at the same time providing for the bodily return of all leaves previously exposed to an inoperative position for the reuse of their data.

The means to accomplish this result forms the subject-matter of the present invention, and as indicated involves the clip 14 in the form of a narrow strip of metal having a lower main length 15, an upper relatively offset section 16, with the free end of the upper section projected outwardly at 17 and downwardly at its free end at 18, forming a holding lip which is preferably convergent toward its free end, with such free end slightly rounded, as shown. The outwardly extending portion 17 is preferably provided with an upstanding projection 19 forming a finger hold for the manipulation of the clip.

The extreme lower or free end of the main length 15 is formed with an elongated slot 20, and the clip is arranged for cooperation with the backing by mounting the clip on

a pivot pin or rivet 21 extending through the several sheets of the backing and through the slot 20 of the clip whereby the clip is permitted a vertical movement as well as a swinging movement. The upper offset section 16 of the clip is exposed through a slot 22 formed in the facing sheet of the backing, the upper length, by reason of the offset, overlying the facing sheet of the backing above the slot. Furthermore, by reason of the offset upper portion, the side margins of the slot 22 form a limit for the respective swinging movements of the clip, for it is important that the swinging movements of the clip be limited in both directions at particular points in order to effect successive release of the leaves.

The upper edges of the leaves 12 are notched at 23, with the notches of appropriate size to permit the free passage therethrough of the lip 18 of the clip. The notches of immediately succeeding leaves are out of alignment and arranged respectively at opposite limit positions of the clip. For example, the notch in the first leaf to be released will be in position to align with the lip 18 of the clip when the clip has been swung to a position to engage one wall of the slot 22. The notch in the next succeeding leaf will be arranged in the upper edge of that leaf in position to be in alignment with the lip 18 of the clip when the clip has been swung to a position to engage the opposite wall of the slot 22. Thus, alternate leaves have their notches in alignment with the opposite limit swinging positions of the clip.

In normal position, all the leaves are in their inoperative positions, i. e. with their data side concealed and supported on the in-turned portion 10 of the guides 6, with the clip occupying an intermediate position between the side walls of the slot 22 and thus out of line with any notches in the leaves. The distance between the upper offset portions 16 of the clip and the lip 18 is such as to readily accommodate the aggregate thickness of all leaves. In this connection, it is understood that, if desired and as indicated, the number 1 corresponding to the first day of the month may be printed directly on the backing instead of on a leaf, although this is optional.

When desiring to expose the data on the outermost leaf in inoperative position, the clip is swung in a direction to align with the notch in that particular leaf, and when the swinging movement of the clip has reached the proximate end wall of the slot 22, the lip is in alignment with the notch in the outermost leaf, the leaf is free of any retaining effect by the clip, and gravitates on the guide strips to expose its opposite side in a position to hold the guide strips. As the notch in the second leaf or next succeeding leaf is at the opposite end of the limit of 120

movement of the clip, the second leaf and thereby all successive leaves are held in inoperative position. When desiring to expose the next leaf, the clip is swung to its opposite limit, aligning the lip 18 with the notch 23 in such leaf and the leaf is free for gravitation or removal to the exposed position. Thus, by merely moving the clip successively in opposite directions, the succeeding leaves 5 are automatically delivered from inoperative to operative or exposed position. Having reached and exposed the particular leaf indicating the final day of the particular month, it is necessary to return all leaves to 10 inoperative position for the indication of the days of the succeeding month. Of course, even under the construction described, the leaves might be returned separately, moving the clip each time to permit the notch in the 15 leaf being returned to pass beyond the lip 18. This is a somewhat tedious operation, however, and would ordinarily not be performed by the user merely for calendar data, and thus the effectiveness of the perpetual calendar 20 would be curtailed. Provision is made, however, for the return of all exposed leaves at a single operation, thus simply and conveniently providing for the restoring of the calendar for continued reuse. This is accomplished by first moving the clip upwardly 25 through the permissible movement afforded by the slot 20. This movement is such as to dispose the extreme lower edge of the lip 18 above the uppermost edges of the leaves when 30 the latter are in inoperative position. All leaves may now be moved from exposed position to inoperative position at one time and, having been placed in the inoperative position, the clip is simply moved downwardly 35 to cause the lip 18 to overlie the outermost leaf. Thus, the restoration of the leaves to an inoperative position is accomplished in a simple, expeditious manner and one which would be ordinarily undertaken by the user 40 of the calendar owing to the comparatively slight time and labor involved and thus the effectiveness of the perpetual calendar is continued.

The clip, therefore, provides a means which 45 through its swinging movement provides for the automatic release of each succeeding card selectively by merely swinging the clip in one direction or the other, the clip also providing for the return of all exposed cards to an inoperative position as a unit and the subsequent positioning of the clip to carry out the automatic single card discharge as described. As stated, the type of perpetual calendar is unimportant so long as it includes the successive exposure of leaves or cards bearing 50 calendar data which is to be continually reused for calendar information.

Under these conditions, the improved clip 55 which forms the subject-matter of the present invention is admirably adapted for the

convenient delivery or discharge of successive calendar leaves or cards from inoperative to exposed position, while at the same time permitting the return of all exposed cards to inoperative position as a unit. Of course, it is contemplated that the cards are to be utilized in addition to their calendar function for advertising or other purposes, for in inoperative position one surface of each card is fully exposed, while, however, 70 concealing the calendar data on that card. The sides of the cards, therefore, which are not necessary for the calendar data may be used for any other purpose, such as advertising, detailed information or the like, as each card in inoperative position remains exposed as to that surface not containing calendar data as long as the previously delivered card remains in exposed position to disclose the calendar data. Therefore, the exposed surface of the cards when in inoperative position may be used for any information, advertising or data desired. 75

The calendar proper may be formed in any way and the exposed surface thereof, other than that occupied by the cards, provided with other calendar data or information, as none of these details form any part of the subject-matter of the present invention and any and all variations in this particular are contemplated. 80

I claim:—

1. A calendar including a backing, a plurality of calendar cards bearing calendar data, means whereby the cards may be moved from an inoperative position with the calendar data concealed to an operative position with the calendar data exposed, the similar edges of all cards being formed with notches, with the notches of alternate cards aligned and the notches of successive cards spaced apart, a clip mounted in the backing for swinging and sliding movement and having holding cooperation with the cards, the swinging movement of the clip freeing the cards successively from the holding influence of the clip and the sliding movement of the clip freeing all cards from the holding influence of the clip. 90

2. A calendar including a series of cards bearing calendar data on one face, means for supporting the cards from movement to a position concealing the calendar data to a position exposing said data, the similar edges of each card being notched, with the notches of successive cards spaced apart and the notches of alternate cards in alignment, a clip mounted for swinging and sliding movement and having a lip to overlie the outermost card of the cards in inoperative position, the swinging movement of the clip permitting the lip to align with the notch of the outermost card to release said card for delivery to an exposed position, the sliding movement of the clip moving the lip to a position free of 95 100 105 110 115 120 125 130

any holding relation with any of the cards.

3. A calendar including a backing, a series of calendar data bearing cards, means carried by the backing to permit the cards to move from an inoperative position with the calendar data concealed to an operative position with the calendar data exposed, a clip having swinging and sliding cooperation with the backing, said clip including a lip to overlie the upper edges of the cards in inoperative position and prevent movement of said cards to exposed position, the upper edges of the cards in inoperative position being formed with notches of a size to permit passage of the lip therethrough, the notches of successive cards being arranged respectively in alignment with the opposite swinging limits of the clip, the sliding movement of the clip arranging the lip wholly above the upper edges of the cards when in inoperative position.

4. A calendar having a backing sheet, a series of cards, guides on which the cards are mounted, said guides being secured to the backing sheet and providing an upper or inoperative position of the cards and a lower or operative position therefor, a clip mounted on the backing for swinging and sliding movement with respect thereto, said clip extending through a slot in the backing, with the terminal walls of the slot limiting the swinging movement of the clip, the upper edges of the cards when in inoperative position being formed with notches alternately aligning with the limit swinging positions of the clip, whereby the clip at each swinging limit will successively release the foremost card, the sliding movement of the clip removing the clip from any holding influence on the cards.

5. A calendar including a backing, a plurality of calendar data bearing cards, means carried by the backing for supporting the cards for movement toward an upper inoperative position to a lower operative position, the cards when in inoperative position concealing the calendar data and when in operative position exposing the data, a clip mounted on the backing for swinging and sliding movement with respect thereto, said clip including a lip to overlie the outermost card when the cards are in inoperative position, said cards being formed in their similar edges with notches, the notches of succeeding cards being spaced apart and the notches of alternate cards being in alignment at right angles to the backing, said clip including a lip capable of passing through the notches and adapted to overlie and hold the outermost card when the lip is out of alignment with the notch therein, means carried by the backing to limit the respective opposite swinging movements of the clip to a position to align the lip with the notches in the cards aligned in such limit position, the sliding movement of the clip moving the lip above the upper edges of the

cards in inoperative position whereby the exposed cards may be returned to inoperative position as a unit.

6. In a perpetual calendar, a relatively flat backing, a series of cards bearing calendar data on one side, means carried by the backing for supporting the cards in position to conceal the data or in a position to expose the data, an element carried by the backing and operatively movable to successively release the outermost card of the cards when in inoperative position to permit said card to be moved to an exposed position, said element being individually movable relative to that portion of the backing on which it is mounted to free all of the cards when in inoperative position simultaneously.

In testimony whereof I affix my signature.
